Attorney

UNITED STATES PATENT OFFICE

FREDERICK H. BALDUF, OF BINGHAMTON, NEW YORK

NAME PLATE

Refile of abandoned application Serial No. 295,759, filed July 27, 1928. This application filed October 1, 1929. Serial No. 396,542.

This invention relates to new and useful improvements in signs, and particularly to signs in the form of name plates.

This is a refile of the abandoned application filed July 27, 1928, Serial Number 295,759.

One object of the invention is to provide a device of this character which is simple in construction, and which can be manufactured 10 at a comparatively low cost.

Another object is to provide a device of this character wherein a plurality of movable and removable letter carrying plates are adapted to be placed, whereby to permit displaying various names or legends.

Other objects and advantages will be apparent from the following description when taken in connection with the accompanying drawing.

20 In the drawing:

Figure 1 is a front elevation of a name plate made in accordance with the present invention.

Figure 2 is a vertical transverse sectional view on the line 2—2 of Figure 1.

Figure 3 is a horizontal sectional view on the line 3—3 of Figure 1.

Figure 4 is a sectional perspective view of the movable letter plate carrying member 30 of the device.

Referring particularly to the accompanying drawing, 10 represents the outside frame of the device, which is preferably formed from a sheet of metal having a rectangular 35 sight opening 11 therein, the edge portions of the plate, surrounding the opening, being bent inwardly at an obtuse angle, as shown at 12. The portion of the frame, or escutcheon, outwardly of the said opening 11, is approximately concavo-convex.

Arranged to be disposed within the escutcheon 10 is a frame 13, which is formed from a sheet of metal having a rectangular, elongated opening 14 therein, flanges 15 being 45 struck out from the longer edges of said opening, and each of said flanges having its free long edge rebent, as at 16, to form the channel or groove 17. A metal plate 18 is slipped in said groove 17, whereby to close the rear of 50 the frame. The upper and lower longer

edges of the frame 13 are formed with the tabs 19, which are adapted to be bent inwardly, for engagement with the upper and lower edges of the changeable letter carrying plates 20, whereby to retain said plates in proper 55 position. Each end of the plate or frame 13 is offset rearwardly, as at 21, and is apertured for the reception of a fastening device 22, by means of which said frame may be secured to a support, such as a door, wall, or 60 porch post, or the like. When the letter plates have been properly positioned on the frame 13, the tabs 19 are pinched tightly thereagainst, and the frame secured to the door, wall, or the like, by passing nails or 65 screws through the apertures 23 formed in the end tabs 24, of such frame. The escutcheon is then secured to the door or wall, by placing the same in such position that the 70 portions 12 contact with the outer faces of the letter plates 20, as clearly seen in Figures 2 and 3, of the drawing. Each end of the outer, or face portion of the frame 13 is formed with a tab 25, which is adapted to be 75 bent outwardly into the paths of the end plates 20, whereby to maintain said plates against lateral displacement, from the ends of the frame. Nails or screws are passed through the corners of the escutcheon, and 80 into the door, wall, or the like support.

What is claimed is:

1. A sign including a plate having an opening, walls extending angularly from the marginal edges of the opening for contact with a support to space the plate therefrom, 85 attaching ears at the ends of the plate, a plurality of letter plate retaining tabs on the margins of the plate, a stop tab on each end of the plate, and an escutcheon plate arranged in covering relation to the first plate 90 and having a sight opening registering with the opening of the first plate.

2. A sign including a plate having an opening the walls of which have angularly extending flanges terminally crimped to form plate receiving grooves, the peripheral edge of the plate having bendable letter plate retaining tabs, bendable stop tabs at the ends of the plate for retaining letter plates, attaching ears on the ends of the plate, a plate re- 95 100

movably supported in said grooves, removable letter plates retained in place by said tabs, and a concavo-convex escutcheon plate disposed in covering relation to the first plate having a sight opening registering with the opening of the first plate, the walls of the opening of the escutcheon plate being directed inwardly against the outer faces of the letter plates.

10. In testimony whereof, I affix my signature.

FREDERICK H. BALDUF.
